UNITED STATES PATENT OFFICE.

CHARLES R. WITTEMAN, OF RICHMOND, NEW YORK.

DISH-WASHING MACHINE.

1,200,289.

Specification of Letters Patent.

Patented Oct. 3, 1916.

Application filed February 7, 1914. Serial No. 817,099.

To all whom it may concern:

Be it known that I, CHARLES R. WITTEMAN, a citizen of the United States, and resident of the borough of Richmond, in the county of Richmond and State of New York, have invented certain new and useful Improvements in Dish-Washing Machines, of which the following is a specification.

This invention relates to dish washing machines, and my improvements are directed toward means whereby dishes and other articles of table use may be automatically and thoroughly cleansed without occasioning the wetting of the hands of an operator.

In brief my said improvements comprise a receptacle having a removable basket or support for the articles to be washed, a jacket about said receptacle, an adjustable connection between said jacket and a source of water supply, means for introducing pressure jets of water into said receptacle from said jacket, an overflow outlet from said receptacle, and a valved drainage outlet.

In the drawing, Figure 1 is a vertical section of my improved dish washing machine, showing its mode of connection with a faucet. Fig. 2 is an enlarged partial end sectional view of the receptacle showing the overflow. Fig. 3 is a corresponding side view, showing the inlet. Fig. 4 is an enlarged side elevation of the drainage valve, and Fig. 5 is a section on the line 5—5 of Fig. 4.

In carrying out my said improvements I provide a receptacle, as *a*, which may be rectangular in form and of suitable dimensions. Said receptacle is supplied with a hollow, belt-like portion, as *b*, serving as a water jacket or chamber, which is provided with suitable means of communication with a faucet, or other pressure supply of water.

As illustrated, the water jacket or chamber *b* is formed by enlarging or expanding the receptacle *a*, externally, in an intermediate, horizontal zone about its walls, and by covering said expanded portion, within the receptacle, with sheet material, as *c*, the inner surfaces of the materials of the main portion of the receptacle, and of the sheet *c*, being conterminous, to thereby provide smooth continuous inner wall surfaces within the receptacle.

A water space, as *d*, exists between the expanded receptacle portion *b* and the sheet *c*, and said sheet *c* is provided with orifices *c'* for the introduction of jets of water into

the receptacle. It being my purpose to cause the jets of water to issue from their orifices with the maximum of force available, said orifices are tapered inwardly, and as the general thickness of the sheet *c* would not, without an undue increase in weight, be sufficient to allow the formation of these tapered orifices, I provide thickened portions of said sheet, as by the solid horizontal ribs *c²*, and locate the tapered orifices in these ribs. The tapered orifices are drilled or otherwise formed in different angles, whereby the streams of water they introduce into the receptacle will be directed, some straight across said receptacle from all sides, and other obliquely in different angles, relatively to the wall surface from which they issue.

Water is introduced into the space *d* as 75 through an elbow or other branch connection *e*, communicating with said space and extending from the outer surface of the receptacle, for connection, as by detachable tubing *f*, with a water faucet. Said pipe 80 connection may carry a cup, as *e'*, to contain a grease solvent capable of feeding in with the inflowing water, whereby the water in its passage through said connection may become charged with such ingredient.

An overflow outlet, as *g*, is provided near the upper portion of the receptacle, and is intended to carry off the top water and floating matter in the operation of the washer. Said overflow outlet is in the form of a depending duct connecting with a broad slot in the receptacle to be of ample capacity for the performance of its function. The end wall of the receptacle at which this overflow outlet is situated is intended to overhang a sink or other waste when in use.

The receptacle is also equipped with a drainage outlet, as *h*, near its base, which may for convenience be located on the same side of the receptacle as the overflow outlet, that 100 it may also overhang the sink or waste. Said outlet *h* is provided with a pivotal valve, as *i*, adapted to be swung upwardly to uncover said outlet, said valve having a supporting stop *h'* to limit its further movement when the outlet is fully uncovered, so that said valve is retained in the open position in convenient manner for handling in closing; and said outlet is provided with a stop *h²*, to limit the forward closing movement of the valve.

A basket, as *j*, which may be of strong

wire, in large mesh, is adapted to be removably fitted in the receptacle to contain the dishes and other articles to be washed. The base of said basket may be corrugated, as by using vertically corrugated warp or weft strands, or by crimping said base, thereby providing a base which will afford a sufficient clearance between the articles supported and the bottom of the receptacle, to allow the passage of fluid therebetween. Said basket has handles, as *j'* whereby it may be conveniently placed within and removed from the receptacle.

In the operation of my improved washer a basket containing articles to be washed is placed within the receptacle, which latter is then covered with a lid, as *k*. Connection is then made between the elbow *e* and a faucet by means of the flexible tubing *f*, whereupon water under pressure enters the space *d*, and issues into the receptacle from orifice *c'* in form of forcible streams or jets from all four sides across the receptacle in different angles, these jets impinging against the articles in the basket and attacking the soluble matter thereon. If the receptacle be allowed to fill with water the overflow will pass off through outlet *g*, carrying therewith the dislodged matter, and if it be desired to continue to exercise the stream force of the jets, the valve *i* is opened to permit discharge through outlet *h*. It should be noted that the water in the receptacle is agitated and caused to circulate therein by reason of the arrangement of the jet orifices in suitable angles, and that the movement of the body of water in the receptacle aids in the cleansing operation.

I have found in practice it to be desirable to employ cold water at first, especially where egg, flour and other foods or condiments, more readily soluble in cold water, are to be attacked, and subsequently to transfer the pipe connection to the hot water faucet to complete the operation. When the washing has been completed the basket containing the articles can be lifted out from the receptacle, and if necessary put in a warm place for drainage and drying, after which the articles will only need polishing with a

dry cloth. The lid or cover *k* has a flat top surface, and its handles *k'* do not project above said top surface, so that when not covering the receptacle said lid may be reversed and placed flatly upon a table to serve as a tray. 55

I claim:

1. An apparatus of the character described comprising a receptacle having an outwardly expanded horizontal portion in its wall, an inner covering plate for said expanded portion, forming a water chamber, said plate having thickened portions provided with jet orifices directed toward the interior of said receptacle, and means of connection between said chamber and a source of water supply. 60 65

2. An apparatus of the character described comprising a receptacle having an outwardly expanded horizontal portion in its wall, an inner covering plate for said expanded portion, forming a water chamber, said plate having a series of parallel solid ribs provided with series of jet orifices 75 directed toward the interior of said receptacle, and means of connection between said chamber and a source of pressure water supply. 70

3. An apparatus of the character described, comprising a rectangular receptacle having an intermediate, horizontal, outwardly expanded portion about its walls, a continuous inner covering plate for said expanded portion, conterminous with the main portions of the receptacle walls, said extended portion and plate forming a water chamber, and said plate having a series of solid parallel ribs provided with series of jet orifices directed toward the interior of 80 85 90 said receptacle, a branch from said water chamber for connection with a source of pressure water supply and an open-work basket removably fitting within said receptacle, to contain the articles to be washed. 95

Signed at the borough of Manhattan in the city, county, and State of New York, this 5th day of February, A. D. 1914.

CHARLES R. WITTEMANN.
